ATTORNEY

UNITED STATES PATENT OFFICE

RICHARD HEINRICH, OF BERLIN-SUDENDE, GERMANY, ASSIGNOR TO WESTINGHOUSE ELECTRIC & MANUFACTURING COMPANY, A CORPORATION OF PENNSYLVANIA

ELECTRICAL PRECIPITATOR

Application filed July 23, 1930, Serial No. 470,025, and in Germany July 23, 1929.

My invention relates to electrical precipitators and specifically to an arrangement for cleaning the electrodes of electrical precipitators.

In electrical purifying plants, the electrodes must now and then be cleaned of the dust depositing itself upon them. This is generally done by shaking the discharge and collecting electrodes by means of special shaking devices and so causing the dust to fall off the electrodes. In small precipitating plants, the arrangement of such special shaking devices makes production and attendance very expensive. In the following 15 an arrangement will be described representing a simplified manner of cleaning the electrodes.

According to my invention, the whole precipitator is elastically suspended and provided with a device causing the precipitator to vibrate. It is by this means possible to free the electrodes, as well as also other surfaces of the precipitator, from the deposited material.

The arrangement may be advantageously made in such manner that the precipitator is provided with a device which knocks it, preferably at regular time intervals, down upon a stationary part. The arrangement 30 may also be made in such manner that a knocking device, for example, a magnetically controlled hammer, is employed which knocks upon a device formed as an anvil and fitted to the precipitator. Through the blows

35 of the hammer, the precipitator is caused to vibrate violently, whereby the deposited material in the precipitator is shaken off.

In the drawing, an example for the carrying into effect of the invention is illustrated; the drawing is an elevation of the example.

1 is an electrical gas-purifying chamber, in which are arranged in a known manner, not shown in the drawing, discharge and collecting electrodes, by which the particles 45 floating in the gases streaming through the chamber are precipitated and fall into the dust-collecting bin 2 situated below the chamber, from where they can, from time to time, be removed. The gas purifying chamber is joined by means of the connecting

branch 3 to the gas-inlet pipe and, by means of the connecting branch 4, to the gas-outlet pipe, leading to the point of consumption. 5 and 6 are high-tension insulators, from which the discharge electrodes inside the chamber 1 are suspended. 7 is a lead carrying the current to feed the electric field between the electrodes. 8 are pedestals serving to support the purifying chamber 1. The latter does not rest directly upon the pedestals 8, helical springs 9 being arranged between the chamber 1 and the pedestals 8. When shaken, the purifying chamber 1 can, therefore, vibrate. On the top of the purifying chamber 1, an electromagnet 10 is fitted and connected, by the leads 11 and 12, to the supply circuit 13. In the lead 12, an interrupter 14 is provided. In the electromagnet, an iron core 15 is placed serving as a hammer, which is lifted, when the switch 14 is closed. As soon as the switch 14 is opened, the iron core drops and falls upon the anvil-plate 16 arranged on the top of the chamber 1. The whole purifying chamber 1 is thereby shaken so that the dust deposited on the electrodes in the chamber falls into the collecting bin 2 below. As the length of the vibrations of the purifying chamber 1 only amounts to a few millimetres, it is mostly not necessary for elastic joints to be provided for the connecting pieces 3 and 4 serving to connect the purifying chamber 1 with the gas-inlet pipe and outlet-pipes.

I claim as my invention:

1. A device for purifying gases electrical- 80 ly consisting of an electrical gas-purifying chamber, connecting pieces suitable for connecting said chamber with a gas inlet-channel and a gas-outlet channel, devices by which the purifying chamber is supported 90 in such manner as to be able to vibrate, and means for making the purifying chamber vibrate.

2. A device for purifying gases electrical- 95 ly consisting of an electrical gas-purifying chamber, connecting pieces suitable for connecting said chamber with a gas inlet-channel and a gas-outlet channel, springs by which the purifying chamber is supported 100 in such manner as to be able to vibrate, and

- devices for shaking the purifying chamber.
3. A device for purifying gases electrical-
ly consisting of an electrical gas-purifying
chamber, connecting pieces suitable for con-
necting said chamber with a gas inlet-chan-
nel and a gas-outlet channel, pedestals for
the purifying chamber, springs arranged be-
tween the pedestals and the purifying cham-
ber, and devices for shaking the purifying
chamber.
- 10 4. A device for purifying gases electrical-
ly consisting of an electrical gas-purifying
chamber, connecting pieces suitable for con-
necting said chamber with a gas-inlet chan-
nel and a gas-outlet channel, devices by which
the purifying chamber is supported in such
manner as to be able to vibrate, and an electro-
magnetically controlled hammer suitable for
making the purifying chamber vibrate.
- 15 5. A device for purifying gases electrical-
ly consisting of an electrical gas-purifying
chamber, connecting pieces suitable for con-
necting said chamber with a gas-inlet chan-
nel and a gas-outlet channel, devices by
20 which the purifying chamber is supported
in such manner as to be able to vibrate, an
electromagnetically controlled hammer for
making the purifying chamber vibrate, and a
device fitted to the purifying chamber and
25 serving as an anvil for the hammer.
- 30 In testimony whereof, I have hereunto
subscribed my name this 9th day of July,
1930.
